UNITED STATES PATENT OFFICE.

WILLIAM FRANKLIN ADAMS, OF MERIDIAN, TEXAS, ASSIGNOR OF THREE-FOURTHS TO GEORGE M. SCALES, GEORGE T. HALLEY, AND JAMES D. THOMAS, OF IREDELL, AND WILLIAM A. AGEE, OF HAMILTON COUNTY, TEXAS.

CAR-COUPING.

SPECIFICATION forming part of Letters Patent No. 629,884, dated August 1, 1899.

Application filed December 30, 1898. Serial No. 700,722. (No model.)

To all whom it may concern:

Be it known that I, WILLIAM FRANKLIN ADAMS, a citizen of the United States, residing at Meridian, in the county of Bosque and State of Texas, have invented a new and useful Car-Coupling, of which the following is a specification.

This invention relates to automatic car-couplers, and has for its object to provide that class of couplers having a pivoted latch with improved means for placing the latch in position and for disengaging the latch from the coupling-link.

To this end the present invention consists in the combination and arrangement of parts, as will be hereinafter more fully described, and particularly pointed out in the claims.

In the drawings, Figure 1 is a perspective view of the coupler applied to the end of a car. Fig. 2 is a longitudinal sectional view thereof. Fig. 3 is a top plan view, the top of the draw-head being removed. Fig. 4 is a detail perspective view of the pivoted latch and adjusting-lever removed. Fig. 5 is a detail perspective view of a modified form of link.

Corresponding parts in the several figures of the drawings are denoted by like reference characters.

Referring to the accompanying drawings, 1 designates the end of any ordinary car, and 2 the draw-head fitted thereto.

The latch for engaging and holding the link 3 in the draw-head is illustrated in detail in Fig. 4, and consists of a solid flat body 4, having the bearing lugs or journals 5 at one end and upon opposite sides thereof and bifurcated longitudinally, as at 6, at the opposite end of the latch. A latch-releasing lever 7 is pivoted intermediate its ends in the bifurcation of the latch, the long arm of the lever extending upward and having an offset fulcrum-heel 8, extending out beyond the end of the latch and below the same. The lugs 5 of the latch have a bearing in opposite notches 9, provided in the side walls and at the upper side of the mouth of the draw-head, and the latch-adjusting lever 7 extends up through a longitudinal slot 10, formed through the top 50 of the draw-head.

The means for operating the latch comprises a rock-lever 11, mounted transversely across the end of the car, having a handle 12 at its outer end and an eye 13 at its other end. This eye extends longitudinally of the draw-head and has a connection 14 with the protruding end of the latch-releasing lever 7. This arrangement affords a means for operating the device from the side of the car. To operate it from the top of the car, a lever 15 is pivoted transversely across the end of the car, near the top thereof, and a suitable connection 16 is provided between said lever and the eye 13 of the rock-lever 11. A suitable stop 17 holds the lever at a convenient point 60 for operation and prevents the same from dropping down out of reach from the top of the car.

The link 3 is provided at each end with a thickened or enlarged portion 18. This enlarged portion extends beyond one face of the link and provides a shoulder 19. In Fig. 5 is illustrated a modified form of link having only one enlarged end 19^a, while the other end thereof has the form of an ordinary link, 75 to be used with the ordinary pin form of coupling.

In the operation of the coupling, the link being inserted into the draw-head, the free end of the latch is forced upward by contact 80 therewith until the enlarged end of the link passes beyond the latch and the latter drops in front of the shoulder 19. A stop 20 limits the inward movement of the link, so that when the latch drops off from the enlarged end 85 thereof it immediately engages with the shoulder 19. When strain is brought upon the link, the free end of the latch is drawn tightly down upon the link and the front end is wedged tightly against a transverse stop-shoulder 21, formed across the upper side of the mouth of the draw-head. Thus the latch is firmly wedged against the shoulder of the link, and resting across the upper face of the link precludes the possibility of the latter being jolted out of engagement by the movement of the train.

To uncouple the cars, either of the levers 11 or 15 is operated to draw the upper protruding end of the latch-releasing lever to 100

ward the car, which movement raises the latch out of engagement with the shoulder 19 of the link by reason of the heel 8 of the adjusting-lever having a fulcrum-bearing upon 5 the enlarged end of the link.

It will be understood that as the heel 8 of the releasing-lever bears upon the shoulder of the link the latter is held flat against the bottom of the opening in the draw-head, so

10 that the latch may be readily disengaged from the shoulder of the link. If the shouldered end of the link were not held down, it would be raised with the latch and the uncoupling operation would be very imperfectly performed.

15 The heel 8 of the releasing-lever therefore performs two distinct functions—viz., forming a fulcrum for the lever and holding the link down while the latch is being released.

In order that the latch and its releasing-lever may be easily placed within the draw-head, each inner side wall thereof is provided with a groove 22, extending upwardly and inwardly from the lower front end thereof.

20 Each of these grooves extends to the top of the bore of the draw-head, where it is widened or enlarged, as shown, and a groove 23 connects the upper end of the groove 22 with the notch 9. To position the latch, the releasing-lever is inserted into the mouth of the

25 draw-head and through the slot 10 in the top thereof, the lugs 5 of the latch engaging the respective grooves 22. The latch is then forced back into the draw-head, the lugs traveling upward in the grooves 22, the lever 7

30 dropping forward in the slot 10, and the heel 8 being received in a recess 24, formed in the stop 20. When the lugs have reached the top of the grooves 20, the latch is forced upward into the recess 25, formed in the top of

35 the draw-head, and then the latch is drawn forward, the lugs passing along the grooves 23 until seated in the respective notches 9. Thus a new latch can be easily placed within 40 the draw-head and the latter may be made in one piece.

By the combination and arrangement as herein set forth an automatic coupler is provided having no springs and consisting of few parts, which may be readily replaced if 45 broken.

Changes in the form, proportion, and minor details of construction and arrangement may be made without departing from the spirit and scope or sacrificing any of the advantages of 50 the present invention.

Having thus described the invention, what is claimed is—

1. In a car-coupler, the combination with a draw-head and a shouldered link, of a latch

5 pivoted to and inclosed entirely within the draw-head and adapted to engage the shoulder of the link, and a releasing-lever pivoted to the latch, and having a fulcrum-heel adapted to bear upon the shouldered end of the link and hold the same down, substantially as and for the purpose set forth.

2. In a car-coupler, the combination with a draw-head and a headed link, of a latch in the form of a flat plate bifurcated longitudinally at one end and provided with opposite bearing-lugs at the opposite end thereof, the lugs

70 being journaled in notches formed in the opposite walls of the draw-head and the latch being wholly inclosed within the same, and a releasing-lever pivoted to the latch

75 within the bifurcation thereof, and having an offset fulcrum-heel adapted to bear upon the shoulder of the link, whereby a fulcrum-bearing is provided for the releasing-lever, and the link is held down while the latch is being released, substantially as shown and described.

3. In a car-coupler, the combination with a draw-head, having a pair of opposite upwardly and rearwardly extending grooves, a pair of opposite notches, and grooves connecting the upwardly-extending grooves with the

80 notches, of a latch having opposite bearing-lugs, said latch being adapted to be placed in position by passing the lugs thereof along the upwardly-extending grooves and then to the

85 notches through the connecting-grooves, the latch being normally inclined downward, a link having a shouldered end and adapted to engage with the free end of the link, and means for disengaging the latch from the link, substantially as shown and described.

4. In a car-coupler, the combination with a draw-head having a pair of opposite upwardly and rearwardly extending grooves, a pair of opposite notches, and grooves connecting the

90 notches and upwardly-extending grooves respectively, formed therein, and a stop-shoulder having a longitudinal recess formed there-

95 in, of a latch having opposite bearing-lugs at one end, and a releasing-lever pivoted inter-

100 mediate its ends at the other end of the latch, a link having a shouldered end, and means for operating said lever to disengage the latch from the link, substantially as and for the purpose set forth.

In testimony that I claim the foregoing as my own I have hereto affixed my signature in the presence of two witnesses.

WILLIAM FRANKLIN ADAMS.
